UNITED STATES PATENT OFFICE

WALTER H. WHEELER, JR., AND AUGUSTUS K. VIELE, OF STAMFORD, CONNECTICUT,
ASSIGNORS TO PITNEY-BOWES POSTAGE METER CO., OF STAMFORD, CONNECTICUT,
A CORPORATION OF DELAWARE

POSTAGE INDICIA STAMP PAD

Application filed April 30, 1930. Serial No. 448,629.

Our invention is a novel pad for use in connection with so-called postage meter machines which ordinarily print postal indicia upon envelopes or ordinary mail matter in lieu of stamps.

The "metered mail" and other postage meter machines now in use, are designed and adapted for printing postage indicia directly upon the envelope or wrapper of each piece 10 of ordinary letter mail; but many pieces of mail are so bulky or of such form that they cannot have postage indicia printed directly thereon by such metered mail machines; and at present the owners and users of such postage meter machines have to carry a supply 15 of the regular adhesive postage stamps to use on the mail matter which the machines cannot handle.

The object of the invention is to provide a 20 novel pad containing strips of paper and which pad can be fed through such postage indicia machines like an ordinary letter and have the postage indicia printed upon strips carried by the pad and the amount of the 25 postage printed on the strip by means of such attachment will be recorded in the meter of the machine to which the attachment is applied exactly as if such indicia had been printed by such machine on normal mail matter. The portion of the strip bearing such 30 indicia can then be severed from the pad and attached to bulky letters or parcels that cannot be operated upon by the standard postage meter machines.

In the accompanying drawings we have 35 shown our attachment as especially designed for use in connection with the postage "metered mail" machine which is fully shown and described in the application of Wheeler and Ogden filed March 8, 1929, Serial No. 345,515, but the invention can be used in connection 40 with other postage meter machines. In the claims we have summarized the essentials of the invention for which protection is desired.

In said drawings:—

Fig. 1 is a partial front view of a postage meter machine showing our novel pad therein in position to be printed. Fig. 2 is a detail side view of Fig. 1. Fig. 3 is a top plan view 50 of the pad detached. Fig. 4 is a side view of

the pad and Fig. 5 is an end view of the pad.

The "metered mail" postage meter machine shown in Wheeler and Ogden's aforesaid application is adapted to postmark and print one or more stamp indicia upon an envelope, 55 and to seal the envelope during its passage through the machine, and to record the value of each stamp, of whatever denomination, that is printed upon the envelope, in a so-called "meter" which can be removed from the machine and taken to the postoffice and "set" for different amounts of prepaid postage, and whereby when the amount of prepaid postage has been used the machine will be automatically locked against further effective operation until additional postage is purchased and the meter reset accordingly. 60

The postage meter machine shown in Wheeler and Ogden's application is provided with a rotatable drum 16 carrying adjustable 70 printing dies and at each rotation of the drum the desired printing die will be brought into operative coaction with an impression roll 111 which is supported upon a yieldable spring-supported plate 112. 75

In operating this machine an envelope is slid flap downward from left to right over the plate 112 until its leading end is in position for operation, then the drum 16 is revolved once, and shortly before the dies arrive at the printing point the envelope will be gripped between the drum and revolving roller and have the indicia printed thereon, and be delivered at the right of the machine, 80 Fig. 2. 85

The said machine is fully described in Wheeler and Ogden's aforesaid application and detailed illustration and description thereof herein is unnecessary.

Said Wheeler and Ogden machine is but 90 one of various machines designed for printing postage indicia upon letters or mail matter to which our invention is adaptable.

Our novel pad preferably comprises a back or base portion 1 preferably of cardboard or paper of sufficient thickness to maintain its shape and support the strip pads mounted thereon. In the example shown two longitudinally arranged strip piles 2 and 3 are 95 mounted upon the base. Each strip pile is 100

composed of a number of strips of paper, about the thickness of an ordinary postage stamp and which may be distinctively marked or colored if desired in any suitable manner. 5 The strips are slightly wider than the width of the impression to be made thereon by the stamp indicia of the postage meter machine. The strips are preferably mucilaged on their under sides so that when removed they can 10 be moistened and readily attached to an envelope or package.

The series of strips in the pile 2 are fastened together at one end 2a, and the series of strips in pile 3 are fastened together at 15 the opposite end 3a. The strips can be successively readily detached by pulling them from the pad. We do not consider the invention limited to having the strips attached at one end only but they should be so attached 20 to the base that they will not be liable to be displaced by contact with the drum or roller but may be readily manually detached as desired.

Further the strip piles 2 and 3 are adjacent, but the base of the pad 1 preferably projects at each side beyond the edge of the adjacent strip pile as indicated at 1a in order to insure that the innermost pile, or the one adjacent the rear flange 112b of the table 112, 25 will be properly spaced away from said flange so that the top strip thereof will be in proper position to receive the impressions from the die 17b when the pad is fed through the machine. While the strips could be made sufficiently wide to cover the margins 1a of the base, if this was done the impressions made 30 on the strips by the machine would not be nicely centered upon the strip, and therefore its printed strip would not present neat appearance when detached from the pad and 35 applied to mail matter.

Two strip piles 2 and 3 are provided so as to enable the successive stamped indicia to be printed upon a strip by the said Wheeler and Ogden machine before the pad is discharged 40 from the machine, in case the amount of postage desired is greater than the face value of any one die, or is the multiple of the face value of any one stamp die, in which case 45 successive impressions can be made upon the strip as the pad is passed through machine, in the same manner that successive impressions may be made upon an envelope as described in the said Wheeler and Ogden application. For this purpose, in said machine, 50 pivoted fingers 13 are employed, see Figs. 1 and 2, and when more than one stamp imprint is to be made upon an envelope or strip the fingers are operated to stop the envelope after 55 each impression until the desired number of impressions are made upon the envelope, as fully described in said Wheeler and Ogden application and therefore need not be described herein. But after the desired number 60 of successive imprints have been made

upon the envelope the fingers are raised and the envelope passes out of the machine. These fingers have to operate upon the envelope out of the path of the dies and the finger 13 engages the body of the envelope 70 at a point below the postage and postmark indicia. Therefore we provide two strip piles (2 and 3) so that in case successive impressions are to be made upon the innermost strip pile the finger 13 will engage the outermost 75 strip pile and will retain the pad in place in the same manner that an envelope could be retained when an envelope is being printed with a successive number of imprints as described in the said Wheeler and Ogden application. 80

If a sufficiently wide strip was used it would not be necessary to put two strip piles on the pad, but such wide strips would be very objectionable because being so much wider than the indicia impressions the resulting stamp torn from the strip would be unsightly when applied to the package. Further by using two strip piles side by side on the pad proper double the number of stamps 90 can be obtained from a given thickness of pad; and the detached strip stamps are of a neat width and appearance. The two strip pads enable one or any desired number of successive impressions to be printed on a strip 95 during one passage of the pad through the machine. By connecting the strips together at the ends 2a, 3a at opposite ends of the pads the leading edge of the strip which is to be printed upon and which comes into contact with the drum and die is held down and cannot curl up or become misplaced in passing into or through the machine; and no matter which end of the pad is introduced into the machine the leading end of the strip to be 100 printed upon is held down.

In use the pad should be reversed on alternate runs through the machine so that the strips 2 and 3 will be alternately printed upon and alternately removed. In this manner the strip piles 2 and 3 will be exhausted equally and kept at a substantially uniform level until all the strips have been printed; and in this way the pads can be 110 utilized most efficiently and satisfactorily.

When mail matter is being stamped by the machine in the usual manner envelopes or packages too bulky to be handled by the machine are to be mailed the operator can put them to one side, and after the uniform mail 120 has been handled, the pad can be run through the machine, by passing either end of the pad to and between the impression roller 11 and the printing drum 16, and the pad will be fed through the machine in the same 125 manner as an envelope, and the stamp indicia will be printed upon the uppermost strip of the innermost pile (2 or 3). After the pad has passed through the machine the printed strip is torn off the pile and the por- 130

tion of the strip bearing the stamp indicia can be moistened and attached to a letter or piece of matter to be mailed, just as an ordinary stamp would be attached thereto.

5 We claim:—

1. A pad for the purpose specified comprising a base, and piles of superposed strips of paper gummed on one side mounted on the base, the piles being arranged side by side, the strips in one pile being connected adjacent one end of the pad, and the strips in the other pile being connected adjacent the other end of the base.

10 2. A pad for the purpose specified; comprising a base and piles of superposed strips of paper, the piles being arranged side by side upon the base, one pile having the strips therein connected together adjacent one end of the base and the adjacent pile having the strips therein connected together adjacent the other end of the base.

15 3. A pad for the purpose specified; comprising a base and piles of superposed strips of paper, the piles being arranged side by side upon the base, one pile having the strips therein connected together adjacent one end of the base the adjacent pile having the strips therein connected together adjacent the other end of the base, the sides of the pad projecting beyond the sides of the piles.

20 4. A pad for use in connection with indicia printing machines and the like; comprising a base and piles of superposed strips arranged side by side on the base; the strips in each pile being detachably attached to each other at one end of the pile, the connected ends of the strips being adjacent opposite ends of the base; said pad being adapted to be passed through the machine like an ordinary envelope, so that the top strip may be printed with indicia, and thereafter detached.

25 5. A pad for use in connection with machines for printing postage indicia; comprising a base, and adjacent piles of superposed strips gummed on one side detachably attached to each other at one end, the attached end of the sheets in one pile being adjacent one end of the pad, and the attached ends of the sheets in the other pile being adjacent the other end of the pad, said piles being attached side by side to the base, the pad being adapted to be passed through the machine like an ordinary envelope so that a top strip may be printed with postage indicia and thereafter detached and applied as a stamp to bulky mail matter.

30 6. A pad for use in connection with machines for printing postage indicia and the like; comprising a base and a pile of superposed strips detachably attached to each other and to the base, the side edge of the base projecting at the side of the strip; said pad being adapted to be passed through the machine like an ordinary envelope so that the

topmost strip may be printed and thereafter detached, the projecting edge of the base guiding and properly positioning the pad relative to the printing die.

7. In a pad as set forth in claim 6, the strips of paper being gummed on their under sides.
